UNITED STATES PATENT OFFICE

170,796

COMBINED COIN HOLDER AND CLIP

Christy M. Del Mas, New York, N. Y., assignor to Michael P. Grace, New York, N. Y.

Application December 12, 1952, Serial No. 22,687

Term of patent 14 years

(Cl. D17—3)

To all whom it may concern:

Be it known that I, Christy M. Del Mas, a citizen of the United States of America, residing at city, county, and State of New York, have invented a new, original, and ornamental Design for a Combined Coin Holder and Clip, of which the following is a specification, reference being had to the accompanying drawing, forming part thereof.

I claim:

The ornamental design for a combined coin holder and clip, as shown.

CHRISTY M. DEL MAS.
